US0D1014896S

(12) **United States Design Patent** (10) Patent No.: **US D1,014,896 S**
(45) Date of Patent: ** Feb. 13, 2024

(54) **BEVERAGE CART**

(71) Applicant: **Dometic Sweden AB**, Solna (SE)

(72) Inventors: **Birk Söödi**, Johanneshov (SE); **Henrik Linder**, Västerås (SE); **Christophe Perez**, Hässelby (SE); **Samuele Meda**, Chichester (GB)

(73) Assignee: **Dometic Sweden AB**, Solna (SE)

(**) Term: **15 Years**

(21) Appl. No.: **29/867,318**

(22) Filed: **Oct. 19, 2022**

Primary Examiner — Cynthia Ramirez

(74) Attorney, Agent, or Firm — Dinsmore & Shohl LLP

(57) **CLAIM**

The ornamental design for a beverage cart, as shown and described.

DESCRIPTION

FIG. 1 is an upper front perspective view of a design of a beverage cart;

FIG. 2 is an upper rear perspective view of the design of FIG. 1;

FIG. 3 is a front view of the design of FIG. 1;

FIG. 4 is a rear view of the design of FIG. 1;

FIG. 5 is a first side view of the design of FIG. 1;

FIG. 6 is a second side view of the design of FIG. 1; and, FIG. 7 is a top view of the design of FIG. 1.

The broken lines in the figures show portions of the beverage cart, which form no part of the claimed design.

1 Claim, 7 Drawing Sheets
